UNITED STATES PATENT OFFICE.

WARREN HURD AND SIMEON B. BROWN, OF WATKINS, NEW YORK.

WALL-PAPER EXHIBITOR.

SPECIFICATION forming part of Letters Patent No. 230,780, dated August 3, 1880.

Application filed October 2, 1879.

To all whom it may concern:

Be it known that we, WARREN HURD and SIMEON B. BROWN, of Watkins, in the county of Schuyler and State of New York, have invented certain new and useful Improvements in Wall-Paper Exhibitors; and we do hereby declare that the following is a full, clear, and exact description of the invention, which will enable others skilled in the art to which it appertains to make and use the same, reference being had to the accompanying drawings, and to the letters of reference marked thereon, which form a part of this specification.

The nature of our invention relates to machines for exhibiting wall-paper; and it consists in certain peculiarities of construction, as will be hereinafter more fully set forth.

In the annexed drawings, to which reference is made, Figure 1 is a front elevation of our improved machine for exhibiting wall-paper. Fig. 2 is a side elevation. Fig. 3 is a transverse vertical section of the same. Fig. 4 is an inside view. Fig. 5 is an outside side view of one of the wheels forming the cylinder. Figs. 6, 7, 8, 9, and 10 are detail views of parts of the machine.

The frame of our machine is composed of two uprights, A A, connected at their upper ends by a cross-bar, B, and having their lower ends curved or bent rearward to form the rear supporting-legs. C C are straight bars or braces secured in an inclined position to the uprights A A, and forming the front supporting-legs.

The legs A C on each side are connected by a brace, D, and the two legs C C are connected by cross-bars E E, to which are fastened slats F F, forming an inclined plane for the paper to fall on for exhibition.

In the uprights A A are made inclined slots a a, to receive and support a horizontal shaft, b, to which the cylinder is secured. This cylinder is composed of a single head, G, a double head, I I', and a series of clamps, H, the heads being fastened by set-screws f f' to the shaft. The single head G is formed on its inner face, near its outer edge, with a series of sockets, d, arranged in a circle concentric with the wheel, the said sockets or recesses being separated by cogs or narrow divisions.

The double head is made in two parts, I and I', the part I being fastened to the shaft b.

This part I is provided with corresponding sockets or recesses d', made in the edge and open at their outer ends. The part I' consists of a flanged ring fitting on the outside of the part I, and completing the sockets or recesses d', and fastened to the part I by screws e or other suitable means.

The clamps H consist each of two bars, connected near one end by a pin, i, and between which the piece of wall-paper h is folded, as shown in Fig. 10. One end of each clamp H is inserted in one of the recesses d on the single wheel G, and the other end slipped into the open recess d', corresponding therewith in the part I on the double wheel. After all the clamps, with their pieces or sheets of paper, have been thus inserted, the flanged ring I' is put on and fastened as above, which completes the cylinder.

The outer end of each sheet or piece h is folded over and fastened down, as shown at x, on the back to form an index to find every sample readily on the cylinder. This can also be done by cutting off a piece from the sample and fastening the same on the back, at or near the lower edge of the sample, with the face side up, or so that it comes in view.

It will readily be seen that by winding the paper or sample around on the cylinder a lap is obtained in such a manner that each sample comes in view and gives an index, and each sample in succession falls upon the exhibiting board or slats E, and is then returned again to the cylinder.

On the outer side of the wheel G is formed a circle of ratchet-teeth, n, into which takes a spring-pawl, m, to prevent any backward movement of the cylinder.

J is a roller on top of the cylinder for holding the samples. The journals of this roller are placed in slots in the uprights, and spring p rests on them for holding the roller down and yet allowing it to yield to the uneven thickness.

K is a weight connected to the top of the frame by a chain, s, and for the purpose of holding the samples from falling when desired. When this weight is not in use it is placed on a shelf, M, at the top of the frame.

L is a cloth fastened to the top of the frame, and extends down the back of the cylinder,

and its lower end is attached to the upper end of the exhibiting-board for protecting the samples.

For some purposes we have found it desirable to shift the paper-cylinder from the bearings a down to the bearings a' , as in packing the machine for transportation, by which means it can be placed in a smaller space, and for this purpose it is necessary that the exhibiting-slats 10 F be made removable. As shown, they are loosely placed in notches in the cross-bars E, which will be found sufficient for ordinary uses. Detachable fastenings may, however, be applied.

15 Having thus fully described our invention, what we claim as new, and desire to secure by Letters Patent, is—

1. In a machine for exhibiting wall-paper, the frame composed of uprights A A, having

curved lower ends, front legs, C C, cross-boards 20 B D E, and the removable open-work or slatted inclined exhibiting-board, substantially as and for the purpose set forth.

2. The combination of the wheel G, formed with the recesses d , the wheel I', having open 25 recesses d' , flanged ring I, and removable clamp H, whereby the cylinder can be filled and revolved in either direction without the paper becoming detached, substantially as set forth.

30 In testimony that we claim the foregoing as our own we have hereto affixed our signatures in presence of two witnesses.

WARREN HURD,
SIMEON B. BROWN.
